UNITED STATES PATENT OFFICE

2,424,127

CONNECTOR FOR WRIST-WATCH BRACELETS AND OTHER LINKAGES

Louis E. Valcourt, East Providence, R. I., assignor
to Kestenman Bros. Mfg. Co., Providence, R. I.,
a corporation of Rhode Island

Application September 13, 1944, Serial No. 553,899

2 Claims. (Cl. 59—82)

1

This invention relates to an improved connector or fastening device for attaching the ends of bracelets to wrist-watches or connecting linkages, cords or the like to other articles.

One object of the invention is to provide a connector at the end of a bracelet or other linkage which is adapted to engage through a loop or bail on the watch-case or to a secondary connecting element carrying a pin having its ends engageable with holes in the spaced lugs of a watch-case.

Another object is to provide a connector of the type specified which is adapted for secure attachment to the end of the bracelet or linkage and for interchangeable connection with a bail on the watch-case or a loop on a secondary connecting element by simple and convenient adjustment.

Another object is to provide a device of the type specified comprising two members, one of which is permanently fastened to the end link of the bracelet or linkage, and the other member constructed in the form of an open ring releasably fastened to the first member and adapted to rotate thereon to engage it through a loop on the watch or other article to be connected.

Another object is to provide a device of the type specified in which the open ring may be fixedly secured to the permanent member on the end of the bracelet or linkage to prevent it from turning thereon or from being otherwise displaced to cause it to release its connection with the watch or other article.

Another object is to provide a device of the type specified which is of neat and ornamental appearance with its mechanical elements covered and concealed from view at the front when the bracelet or linkage is attached to a watch or other article.

Another object is to provide a device of the type specified which may be constructed from sheet-metal, stamped out and struck up to form to economize in its cost of manufacture.

Further objects of the invention are set forth in the following specification which describes a preferred form of construction of the device as illustrated by the accompanying drawing.

In the drawing:

Fig. 1 is a plan view of a watch with a bracelet attached thereto by means of the present improved connector;

Fig. 2 is an edge view of the same;

Fig. 3 is a greatly enlarged detail view showing one end of a chain or linkage attached to the bail of a watch by means of the present connec-

2

tor which is illustrated in plan view on its under or bottom side;

Fig. 4 is a similar view showing the connector ring as released and rotated to position its opening for inserting it through or removing it from the bail of a watch;

Fig. 5 is an enlarged sectional view on line 5—5 of Fig. 4;

Fig. 6 is an enlarged sectional view on line 6—6 of Fig. 3;

Fig. 7 is a still further enlarged perspective view of the open ring of the connector; and

Fig. 8 is a plan view of a watch showing the ends of a bracelet attached thereto by means of the present connector engaging through the loop on a secondary element pinned to the lugs on the sides of another type of watch-case.

Wrist-watches are provided with different types of attaching means at the sides of their cases. Men's watches are usually provided with a pair of spaced lugs at each side of the case with the lugs drilled with holes for receiving the spring-pressed points or tips of cross-pins held in tubular fittings at the ends of the bracelet. Ladies' watches, however, usually have a different form of attaching means such as a loop at each end of the watch-case for engagement therethrough of a link or ring on the end of the bracelet. The present improved connector is adapted for use with either type of attaching means on the watch-case, that is, it may be engaged with a loop on the watch or, in other cases, it may be engaged through a loop on a secondary or auxiliary element carrying a cross-pin with spring points insertable in the holes in the spaced lugs on the watch-case.

In general, the present improved connector comprises a main member 2 adapted for permanent connection to the end-link of a chain or bracelet and an open ring-shaped member 3 adapted to be secured in fixed position on the main member 2 or to be released from its holding means to permit it to be turned for inserting it through a loop on the watch-case or a loop on the secondary attaching element carrying the cross-pin. The member 2 is preferably of substantially V-outline or fan-shape in plan view and provided at one end with a tongue 4 adapted to loop around the end bar 5 of the end link 6 of the bracelet 10. As shown in Figs. 3 and 4, the member 2 may be constructed of sheet-metal stamped out and formed in dies and preferably it is ornamented by embossing its upper face in any suitable design, as indicated in Figs. 1, 2 and 8. The member 3 is preferably of circular shape,

that is, constructed as a ring with an opening in its circumference and provided with a pair of fingers 11 projecting substantially radially outward from the sides of its opening as shown most clearly in Fig. 7. The member 3 may be formed of wire or constructed from sheet-metal struck up in dies and preferably its main ring-portion has a beveled or rounded contour on its upper surface. The fingers 11, however, may be of generally square cross-section and constructed integral with the ring.

Referring to Figs. 3 and 4 and the sectional views, Figs. 5 and 6, the member 2 is provided with relatively narrow, flat tabs 12 formed by projecting strips of the metal bent downwardly from its top portion 13. The tabs 12 are connected by a circular flange 14 bent down from the edge of the top portion 13 of the member 2 at its wider end and shaped to a contour corresponding to that of the inner curve of the ring-member 3. The tabs 12 are adapted to be inserted through the interior of the ring-member 3 and bent or folded there-around in the manner shown in Fig. 6. To fixedly secure the ring 3 to the member 2 the tabs 12 are bent or folded around the circular portion of the ring-member 3, as shown in Fig. 3, being so located that their edges will be in position to engage with the sides of the fingers 11 to prevent the ring 3 from turning on the member 2.

In use, the present improved connector is applied to each end of a linkage or bracelet 10 by bending its tongue 4 around the end bar 5 of the terminal link 6 and closing it tightly thereagainst as shown in Fig. 2. To attach the end of the bracelet to the loop 8 on the side of a watch-case 9, such as shown in Figs. 1 and 2, the ring-member 3 is first rotated into the position illustrated in Fig. 4 to open it. This rotary movement of the ring may be accomplished when one of the tabs 12 on the member 2 is released, that is, unfolded as illustrated in Fig. 5, and the connector is usually furnished in this condition on the bracelet. The ring-member 3 will still be maintained in engagement with the member 2 by means of the opposite tab 12 which remains folded around the ring so that the latter is held in convenient position for hooking it through the loop 8 on the watch-case 9 as shown in Fig. 4. After the ring-member 3 has thus been connected to the loop 8 on the watch-case 9, it is rotated back to first position as shown in Fig. 3 and the tab 12 bent around the ring. When turned to this position and fastened as explained above, the ring-member 3 is securely held against the main member 2 and prevented from turning thereon by the engagement of its fingers 11 with the edges of the bent tabs 12. It will be noted by reference to Fig. 3 that the fingers 11 are held in close abutting relation to the under side of the member 2 so that they serve to prevent the ring-member 3 from rocking or canting thereon to thereby render the joinder between the two members rigid and secure.

When it is desired to attach a bracelet to a watch of the type illustrated in Fig. 8, that is, one having lugs on the sides of its case, the attachment is made as next explained. The watch-case 19 is usually provided with relatively narrow, spaced lugs 20 drilled with small holes 21. A usual type of connecting device for this style of watch consists in a tubular member 22, see Fig. 8, enclosing a cross-pin 23 formed with spring-pressed projecting points or tips 24. At the center of the tubular member 22 is a loop 25 for con-

nexion with the bracelet. The spring tips 24 are inserted in the holes 21 of the lugs 20 to attach the member 22 to the watch-case and with the use of this auxiliary fitting the present connector 5 may be attached thereto by hooking it through the loop 25 after its ring-member 3 has been rotated on the member 2 to the position shown at the right in Fig. 8. The ring-member 3 is then turned back to first position and fixedly secured 10 to the member 2 by means of the tabs 12 shown in Figs. 3 and 4 and previously described. It will thus be seen that the present improved connector is adapted for attachment to different styles of watch-cases having different types of connecting 15 means so that it is of more or less general application.

Wrist-watch bracelets are generally sold complete with attaching devices or connectors at their ends and the present improved connector is furnished in form for use with different types of 20 watch-cases. The bracelet may be supplied to the jeweler or other retail outlet with the present improved connector attached to its ends and having its ring-member 3 connected to the auxiliary 25 attaching device 22 in the form as shown at the left in Fig. 8. In this form it is adapted for attachment to wrist-watches having lugs at the sides of the case, but when the bracelet is sold for use with a ladies' watch having loops on its 30 sides the jeweler or salesman may readily adapt it for such a connection. To prepare it for this latter use it is only necessary to disconnect the auxiliary member 22 from the ring-member 3 and this may be done by simply opening or bending 35 back one of the tabs 12 on the under side of the member 2 to permit the ring-member 3 to be turned to open position as shown at the right in Fig. 8. The ring-member 3 is then in open position for disengaging it from the auxiliary device 22 and engaging it through the loop 8 on the side of a ladies' watch-case 9 such as shown in Figs. 1 and 2; after which the ring-member is 40 rotated back into the position shown in Fig. 3 and the tab 12 bent to secure it fixedly to the member 2.

It will be observed from the foregoing specification that the present improved connector for 45 wrist-watch bracelets, linkages, cords and other like articles provides an especially simple yet efficient device for attaching bracelets or other linkages, cords and the like to different types of watch-cases and other articles. The present improved connector is of graceful shape and ornamental appearance to embellish the chain or linkage with which it is used while also being economical in cost of manufacture. The device also provides a secure attachment or connection between the bracelet and watch-case, practically proof against accidental disconnection and strong 55 and sturdy to resist unusual strains and stresses.

While the device is herein shown and described as embodied in a preferred form of construction, it is to be understood that various modifications 60 may be made in the structure and arrangement of its parts without departing from the spirit or scope of the invention. Therefore, without limiting myself in this respect, I claim:

1. A connector for wrist-watch bracelets, linkages, cords and the like comprising a relatively 65 flat main member having means for permanently attaching it to the end of a bracelet or the like and provided with angularly-related relatively narrow bendable tabs folded rearwardly from its forward side, and an open ring-shaped member 70 provided with rectangular fingers projecting sub-

stantially radially from the sides of its opening, said ring-member being adapted to underlie the bottom of the main member with one of the tabs thereof bent down around its circular portion whereby said ring-member may be rotated about its own axis with respect to the main member to expose its opening for connecting it to the bail of a watch or other part and then rotated in the opposite direction to position both of its fingers in underlying relation to the main member to adapt the unbent tab to be bent down around its circular portion so that both tabs will enclose said circular portion of the ring-member with their edges abutting the sides of its fingers to secure it against turning on the main member and prevent it from releasing the watch bail or other part.

2. A connector for wrist-watch bracelets, linkages, cords and the like comprising a substantially flat main member embodying means for permanently attaching it to the end of the bracelet or the like and formed with a downwardly-projecting circular flange bordering its forward edge with narrow tabs folded rearwardly from said flange,

and an open ring-shaped member having fingers projecting substantially radially from the sides of its opening, said ring-shaped member being adapted to underlie the main member with its fingers projecting rearwardly thereon and with the inner periphery of the ring abutting the circular flange on said main member with the tabs overlying the circular portion of the ring-member and bent downwardly therearound with their edges in engagement with the fingers thereof to secure the ring-member to the main member and hold it from turning with respect thereto.
